Primary Examiner — Natasha Vujcic*Assistant Examiner* — Gilbert B Ford(74) *Attorney, Agent, or Firm* — Heslin Rothenberg Farley & Mesiti P.C.; Victor A. Cardona, Esq.(57) **CLAIM**

I claim the ornamental design for a drip chamber for medical lines, as shown and described.

DESCRIPTION

FIG. 1 is a perspective view from a first end of a drip chamber for medical lines showing the new design;

FIG. 2 is a perspective view from a second end opposite to first end thereof;

FIG. 3 is a front side view thereof, a rear side view being a mirror image thereof;

FIG. 4 is a right lateral view thereof, a left side view being a mirror image thereof;

FIG. 5 is a first end view thereof; and,

FIG. 6 is a second end view thereof.

The broken lines shown in the drawings illustrate portions of the car that form no part of the claimed design.
